(57) **CLAIM**

We claim the ornamental design for a disposable storage and dispensing bag, as shown and described.

DESCRIPTION

FIG. 1 is a front perspective view of the claimed design with a top slide locking closure mechanism in an closed configuration and a bottom slide locking closure mechanism in an open configuration.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof; and,

FIG. 8 is a perspective view of the claimed design containing contents with the top slide locking closure mechanism in the closed configuration and the bottom slide locking closure mechanism in the closed configuration.

The broken line showing of portions of the disposable storage and dispensing bag is included for the purpose of illustrating environmental structure and forms no part of the claimed design.

1 Claim, 4 Drawing Sheets
